UNITED STATES PATENT OFFICE.

LUCIAN ROSENWALD, OF KANSAS CITY, MISSOURI

COLLAPSIBLE BOX.

1,250,357.

Specification of Letters Patent. Patented Dec. 18, 1917.

Application filed July 27, 1914. Serial No. 853,261.

To all whom it may concern:

Be it known that I, LUCIAN ROSENWALD, a citizen of the United States, residing at Kansas City, in the county of Jackson and State of Missouri, have invented a certain new and useful Improvement in Collapsible Boxes, of which the following is a specification.

My invention relates to improvements in collapsible boxes.

It is particularly adapted for use in berry or fruit boxes.

The object of my invention is to provide a collapsible box of novel construction, which is cheap, strong and durable, and which may be easily and quickly extended or collapsed by an inexperienced person.

The novel features of my invention are hereinafter fully described and claimed.

20 In the accompanying drawing, which illustrates the preferred embodiment of my invention,

Figure 1 is a perspective view of my improved box shown extended and bottom side up.

Fig. 2 is a cross section of the same.

Fig. 3 is a plan view of the bottom member with the flaps horizontally disposed.

Fig. 4 is a plan view of the body of the box collapsed.

Fig. 5 is a plan view of the strip which forms the body prior to its being formed.

Similar reference characters designate similar parts in the different views.

35 1 designates the body of the box, preferably formed from a rectangular strip of suitable material, such as sheet wood or card board, the ends of the strip being overlapped and secured together.

40 The body is provided with a plurality of transverse flexible joints 2, formed by scoring or creasing the material at right angles to the longitudinal edges of the strip

1. The said joints are located at the respective corners of the box, so that the body may be collapsed to the flat form, shown in Fig. 4, or extended to operative position, as shown in Figs. 1 and 2.

45 3 designates a bottom member, preferably flat and formed of suitable material of sufficient thickness, such as card board or sheet wood.

50 The body 1 is provided with lateral openings 4 through which the corners of the bottom member 3 are adapted to respectively project. In the form illustrated, the body

is of the usual berry box form, substantially rectangular, the corners of the rectangle being cut away.

The bottom member 3 is substantially rectangular and fitted in the body 1, the corners of the bottom member being extended through the openings 4 respectively, when the box is set up for use.

To permit of the easy insertion or removal of the bottom member 3, it is provided between opposite edges with a flexible joint 5 arranged to permit the bottom member to be flexed upwardly, but not downwardly, from the horizontal along the joint.

70 Preferably the joint in the bottom member is formed by scoring the underside. This permits of the upward flexing at the joint from the horizontal, but does not permit the member to be bent downwardly, with the ordinary pressure to which it is liable to be subjected, from the horizontal.

75 The bottom member 3 is provided at its edges respectively with flaps 6 flexibly connected with the bottom and adapted to be bent downwardly along or adjacent to said edges so as to form legs, as shown in Figs. 1 and 2, the lower edges of the flaps, when so bent, being, preferably flush with the lower edges of the body 1. These legs 80 serve to stiffen the box, and those at the ends of the box, preferably disposed at opposite sides of the joint 5, prevent the bottom member being flexed downwardly at the joint.

90 To have the flaps flexibly connected with the bottom member, so as to be easily bent downwardly, the under side of the bottom member, adjacent to the places of joinder of the flaps, is provided, parallel with the adjacent edges of the bottom member, with scorings or creasings 7, disposed adjacent to said edges.

95 The ends of the strip 1 are preferably releasably secured to each other by some suitable means. In the drawing, Fig. 5, I have shown the strip 1 provided adjacent to its ends respectively, with two parallel slits 8 extending respectively from opposite longitudinal edges toward the adjacent ends and to a point half way between said edges.

100 In setting up or assembling the box, the strip 1 is bent to the proper form along the joints 2, after which the tongues 9, which are formed at the ends of the strip by the presence of the slits 8, are respectively slipped into the slits 8 of the opposite ends,

the tongues being preferably at the inner side of the box, with the slits 8 in alinement with each other, and with the longitudinal edges of the strip also disposed in alinement with each other at both ends of the strip.

The body will thus have its ends securely and releasably held together, after which the bottom member 3 is bent upwardly along the joint 5 and inserted, with the flaps 6 downwardly bent, into the body 1 in a position such that the corners of the bottom member 3 will enter the slots or openings 4, said openings having sufficient width to permit of such insertion. The bottom member 3 is then bent downwardly along the joint 5 to the horizontal position shown in Figs. 1 and 2, said member having been inserted in the body, with the scored side down.

20 To collapse the box, the operation just described is reversed.

If a non-flexible bottom is employed with the body 1, in assembling, said bottom is inserted in the openings 4 before the ends of the strip 1 are joined.

I do not limit my invention to the structure shown and described, as modifications, within the scope of the appended claims, may be made without departing from the spirit of my invention.

Having thus described my invention, what I claim and desire to secure by Letters Patent, is:

1. A collapsible box comprising a body 35 consisting of a rectangular strip provided adjacent to its ends respectively with two parallel transverse slits which extend respectively from opposite longitudinal edges obliquely toward the adjacent ends and to points respectively half way between said edges, each end of the strip being inserted through the slit which is adjacent to the other end, the slits being disposed in alinement with each other, when the strip is bent 40 to form the body, the strip having transverse flexible joints at the respective corners, the body being provided with lateral openings, and a bottom member adapted to be fitted in said body and adapted to

have its corners extend respectively through 50 said openings.

2. A collapsible box comprising a body consisting of a rectangular strip having adjacent to its respective ends two parallel transverse slits which extend respectively 55 from opposite longitudinal edges obliquely toward the adjacent ends and to points respectively half way between said edges, each end of the strip being inserted through the slit which is adjacent to the other end, 60 the slits being in alinement with each other when the strip is bent to form the body, said ends being at the inner side of the body, the strip having transverse flexible joints at the respective corners of the body, the body 65 having lateral openings, and a bottom member adapted to be fitted in said body and to have its corners extend respectively through said openings.

3. A collapsible box comprising a folding 70 body having corner openings, and a bottom member adapted to have its corners respectively project through said openings, the bottom member being provided with edge flaps extending downwardly and disposed at the inner side of and located wholly within the body and forming legs therefor.

4. A collapsible box comprising a folding 80 body, and a bottom member having a longitudinal joint, and provided at opposite sides respectively of said joint with downwardly extending portions which form legs for holding the bottom from bending downwardly at its joint.

5. A collapsible box comprising a body, and a bottom member having a joint extending from one edge to the opposite edge, and provided with downwardly extending legs adapted to prevent the downward flexure of the bottom member at said joint.

In testimony, whereof I have signed my name to this specification in presence of two subscribing witnesses.

LUCIAN ROSENWALD.
